[57] CLAIM

The ornamental design for a molded electrical insulator, substantially as shown and described.

DESCRIPTION

FIG. 1 is a front elevational view of one embodiment of a molded electrical insulator according to this invention.

FIG. 2 is a top view of the insulator of FIG. 1;
FIG. 3 is a rear elevational view of the insulator of FIG. 1;

FIG. 4 is an end elevational view of the insulator of FIG. 1;

FIG. 5 is a front elevational view of an alternative embodiment of the molded electrical insulator according to this invention;

FIG. 6 is a top view of the insulator of FIG. 5;
FIG. 7 is a rear elevational view of the insulator of FIG. 5;

FIG. 8 is an end elevational view of the insulator of FIG. 5.

FIG. 1FIG. 2FIG-3FIG-4FIG-5
